(57) **ABSTRACT**

A slide actuated key fob includes a housing having a transmitter disposed therein and at least one slide actuated button disposed on the housing. The transmitter sends an actuating signal when the at least one slide actuated button is slidably moved in a first direction and subsequently depressed in a second direction.

SLIDING KEY FOB

This application is a continuation-in-part of commonly owned, U.S. patent application Ser. No. 12/273,900 filed on Nov. 19, 2008, which is expressly incorporated herein by reference.

BACKGROUND

The present disclosure relates to vehicle key fobs, and particularly relates to a sliding or slide actuated key fob for a vehicle.

Portable remote transmitters or key fobs for vehicle keyless entry systems are commonly used to remotely control various vehicle functions. For example, the key fob can include multiple vehicle function switches to remotely accomplish such activities as, for example, locking and unlocking the doors of the vehicle, opening the trunk and/or operating a powered door. Typically such key fobs are button-based designs which require the user to press a button to remotely activate a function on a vehicle. For example, a common vehicle key fob includes a lock button, an unlock button, a trunk unlock/open button and a panic button. A user simply presses the appropriate button to activate a desired function (e.g., unlock vehicle doors) and then the key fob transmits a vehicle function request, whether pressing of the button was inadvertent or not.

One problem which has been associated with such conventional key fobs is that the buttons are prone to inadvertent actuation. Such inadvertent actuation can occur as the key fob is placed in a purse of a user, as the user performs other activities with the key fob in his or her hands, or as a result of being compressed while in a pocket of the user. The misoperation of a key fob function can unintentionally open a powered tailgate, for example, and therefore cause damage (e.g., if the powered tailgate opens into a garage structure or door) and/or make the vehicle insecure without the owner's knowledge. Also, the battery may become inadvertently drained due to prolonged accidental button presses. For example, the key fob may reside in a user's pocket or purse and may be situated such that one or more of its buttons are held in or repeatedly pressed unknowingly by the carrier. This can result in the battery of the key fob undesirably draining.

To deal with inadvertent actuation, some manufacturers employ a sliding door or openable cover that prevents the key fob's buttons from being pushed accidentally. However, these types of key fobs are more cumbersome to operate in that they require the user to first open the door or cover to reveal the buttons and then subsequently press one or more of the buttons to activate a function remotely on the vehicle. In addition to being relatively more cumbersome, this process of opening a door and then pressing a button is more time consuming.

SUMMARY

According to one aspect, a slide actuated key fob includes a housing having a transmitter disposed therein and at least one slide actuated button disposed on the housing. The transmitter sends an actuating signal when the at least one slide actuated button is slidably moved in a first direction and subsequently depressed in a second direction.

According to another aspect, a key fob for a vehicle includes a housing having a slide actuated button disposed thereon and a transmitter disposed in the housing for transmitting actuating signals to an associated vehicle. The transmitter sends an actuation signal only when the slide actuated

button is first moved along a first axis on a face of the housing and then moved along a second axis into the housing.

According to still another aspect, a key fob includes a housing and at least one slide actuated button disposed on the housing. The at least one slide actuated button is sequentially slid in a first direction and then depressed in second direction. A transmitter is disposed in the housing for sending an actuating signal when the at least one slide actuated button is depressed sufficiently in the second direction after having been slid in the first direction.

BRIEF DESCRIPTION OF THE DRAWINGS

FIG. 1 is a perspective view of a sliding key fob formed of first and second housing members.

FIG. 2 is a perspective view of the sliding key fob with the first housing member slidably moved in a first direction relative to the second housing member along a first axis to a first actuating position to actuate a vehicle function.

FIG. 3 is a perspective view of the sliding key fob with the first housing member slidably moved in a second direction relative to the second housing member along a second axis to a second actuating position to actuate another vehicle function.

FIG. 4 is a cross-sectional view of the key fob taken along the line 4-4 of FIG. 1.

FIG. 5 is a cross-sectional view of the key fob taken along the line 5-5 of FIG. 4.

FIG. 6 is a cross-sectional view of the key fob taken along the line 6-6 of FIG. 2.

FIG. 7 is a cross-sectional view of the key fob taken along the line 7-7 of FIG. 6.

FIG. 8 is an exploded view of the key fob of FIG. 1.

FIG. 9 is a schematic cross-sectional view of an alternate sliding key fob.

FIG. 10 is a schematic cross-sectional view of another alternate sliding key fob.

FIG. 11 is a schematic view of a sliding key fob and a vehicle to which the sliding key fob corresponds.

FIG. 12 is a perspective view of still another alternate sliding key fob having a pair of slide actuated buttons disposed thereon.

FIG. 13 is a schematic view of the sliding key fob of FIG. 12.

FIGS. 14A-14C are schematic diagrams illustrating operation of one of the slide actuated buttons of FIG. 12.

FIG. 15 is a schematic plan view of one of the slide actuated buttons of FIG. 12.

DETAILED DESCRIPTION

Referring now to the drawings, wherein the showings are for purposes of illustrating one or more exemplary embodiments, FIGS. 1-3 illustrate a sliding or slide actuated key fob

10 for a vehicle. As shown, the key fob 10 includes a housing 12,14 formed of a first or upper housing member 12 and a second or lower housing member 14. More particularly, the first or upper housing member 12 is secured to the second or lower housing member 14 and is slidably movable relative thereto. In the illustrated embodiment, the first and second housing members are formed as first and second clam shell members, wherein the first clam shell member 12 is slidably movable in at least two directions relative to the second clam shell member 14.

More particularly, in the illustrated embodiment, the upper housing member 12 is slidably movable along a first axis 16 (as shown in FIG. 2) to a first actuating position and slidably

movable along a second axis **18** (as shown in FIG. 3) to a second actuating position. The upper housing member **12** is also slidably movable along the first axis **16** to a third actuating position and slidably movable along the second axis **18** to a fourth actuating position. The first axis **16** of FIG. 2 is oriented approximately normal or perpendicular relative to the second axis **18** of FIG. 3 in the illustrated embodiment. As will be described in more detail below, each of the actuating positions (e.g., first, second, third and fourth actuating positions) can be used to transmit a corresponding actuating signal to a vehicle for purposes of actuating a particular vehicle function (i.e., each position corresponds to a specific vehicle function).

For example, as shown in FIG. 2, the upper member **12** can be moved along the first axis **16** in a first direction as indicated by arrow **20** to or toward the first actuating position to transmit a first signal to the vehicle for actuating a first vehicle function, such as an unlock doors function. In FIG. 3, the upper member **12** is shown being moved to or toward the second actuating position along axis **18** in the direction of arrow **22** to transmit a second actuating signal to a vehicle corresponding to a second vehicle function, such as an open trunk function. Moving the upper housing **12** along axis **16** in a direction opposite arrow **20** to the third actuating position could be used to transmit a third actuating signal to actuate a third vehicle function, such as locking the vehicle's doors. Similarly, the upper member **12** could be moved along axis **18** in a direction opposite arrow **22** to the fourth actuating position to send a fourth actuating signal to the vehicle for actuating a fourth vehicle function, such as a panic function. As will be readily appreciated by those skilled in the art, the housing **12,14** is advantageously button-less (i.e., does not include buttons that require depression for actuation) and instead uses a sliding movement to actuate particular vehicle functions. The upper housing member **12** includes a recess or depression **24** appropriately sized for receiving a user's finger and enabling the user to slidably move the upper housing member **12** relative to the lower housing member **14**.

With reference to FIGS. 4 and 11, a transmitter **28** can be disposed within the housing **12,14**, such as between the first and second members **12,14**, for transmitting actuating signals to a vehicle **30** (e.g., the first, second, third and fourth actuating signals). The key fob **10** can further include a controller **32** operatively connected to the transmitter **28** and powered by a battery **34**. A plurality of micro-switches **36,38,40,42** can also be disposed within the key fob **10** for indicating when the upper housing **12** is moved to one of its actuating positions. The transmitter **28** can send, via antenna **44**, a first actuating signal when the first housing member **12** is slidably moved in the first direction (e.g., the direction of arrow **20**) relative to the second housing member **14** to the first actuating position of FIG. 2. The transmitter can also send a second actuating signal when the first housing member **12** is slidably moved in a second direction (e.g., the direction of arrow **22**) relative to the second housing member **14** to the second actuating position of FIG. 3. Likewise, the transmitter **28** can send the third and fourth actuating signals via the antenna **44** when the first housing member **12** is slidably moved relative to the second housing member **14** to, respectively, the third and fourth actuating positions.

More particularly, as will be described in more detail below, the first micro-switch **36** can be triggered or actuated when the first housing member **12** is moved along axis **16** in the direction of arrow **20** to the first actuating position of FIG. 2 and the second micro-switch **38** can be triggered or actuated when the first housing member **12** is moved along axis **18** in the direction of arrow **22** to the second actuating position of

FIG. 3. The third micro-switch **40** can correspond to the third actuating position, which is achieved by moving the first housing member **12** along axis **16** in a direction opposite arrow **20**, and the fourth micro-switch **42** can correspond to the fourth actuating position, which can be achieved by moving the first housing member **12** along axis **18** in a direction opposite arrow **22**. Triggering or actuating of the micro-switches **40,42** can, respectively, be used by the controller **32** to send third and fourth actuating signals via the transmitter **28** to the vehicle **30**.

The controller **32** directs the transmitter **28** to send the first actuating signal when the first micro-switch **36** is actuated by the first housing member **12** being moved into the first actuating position. The controller **32** directs the transmitter **28** to send the second actuating signal when the second micro-switch **38** is actuated by the first housing member being moved into the second actuating position. The controller **32** directs the transmitter **28** to send the third actuating signal when the third micro-switch **40** is actuated by the first housing member **12** being moved into the third actuating position. The controller **32** directs the transmitter **28** to send the fourth actuating signal when the fourth micro-switch **42** is actuated by the first housing member **12** being moved into the fourth actuating position.

A receiver **46** on the vehicle **30** having antenna **48** can receive the actuating signals from the key fob **10** and deliver the same to an onboard controller **50**. The onboard controller **50**, which can be powered by the vehicle's battery, can process the actuating signals and use the same for operating corresponding functions of the vehicle **30**. For example, the controller **50** can process the first actuating signal to unlock the vehicle's doors **52,54** via unlock/locking mechanisms **56,58**. The second actuating signal can be processed by the onboard controller **50** to unlock and open the vehicle's trunk **60** via trunk latch mechanism **62**. The third actuating signal can be processed by the onboard controller **50** to lock the vehicle doors **52,54** via the unlocking/locking mechanisms **56,58**. Also, the fourth actuating signal can be processed by the onboard controller **50** to initiate a panic alarm, such as through the vehicle's horn and/or lights, or other noise and/or light generating devices **64**. Of course, fewer or more actuating signals and corresponding functions could be used and the function could vary from the illustrated embodiment.

In the illustrated embodiment, the first actuating signal is transmitted when the first housing member **12** is slidably moved from a non-actuating rest position (i.e., the position illustrated in FIG. 1) in a first direction, such as the direction indicated by arrow **20**, along first axis **16** to the first actuating position (the position illustrated in FIG. 2). A second actuating signal is transmitted when the first housing member **12** is slidably moved from the non-actuating rest position of FIG. 1 in the second direction, such as the direction indicated by arrow **22**, along axis **18** to the second actuating position (the position illustrated in FIG. 3). The axes **16,18** and the first and second directions **20,22** are approximately normal relative to one another in the illustrated embodiment.

A third actuating signal is transmitted when the first housing member **12** is slidably moved from the non-actuating rest position in a third direction (e.g., a direction opposite that indicated by arrow **20**) to a third actuating position along the axis **16**. The first and third directions are opposite one another along axis **16**. A fourth actuating signal is transmitted when the first housing member **12** is slidably moved from the non-actuating rest position in a fourth direction (i.e., a direction opposite arrow **22**) along axis **18** to a fourth actuating position, the fourth direction being opposite the second direction

along the axis 18. Of course, the directions need not be limited to those employed in the illustrated embodiment.

As shown in FIGS. 1-3, sliding movement in the first, second, third and fourth directions occurs in a single plane. More specifically, the first, second, third and fourth directions are disposed along a plane defined by an interface 68 formed between the first and second housing members 12,14 and thus sliding movement of the upper housing 12 relative to the lower housing 14 is restricted to a single plane. In contrast to prior art button-based key fobs, the sliding movement of key fob 10 occurs in a plane parallel to a face 12a of the key fob. Prior art button-based key fobs would generally require depression of a button downward into the face 12a (i.e., orthogonal relative to the single plane of key fob 10).

With reference to FIGS. 4, 5 and 8, a base 80, an intermediate member 82 and a cover 84 are secured to the lower housing member 14 via one or more fasteners, such as screws 86. Alternatively, at least the base 80 can be integrally formed with the lower housing member 14. Secured to the upper housing member 12 are an upper housing base 90, an upper housing intermediate member 92 and a printed circuit board (PCB) or substrate 94. In the illustrated embodiment, the PCB 94 is sandwiched between the intermediate member 92 and the upper housing member 12, which are held together via one or more fasteners, such as screws 96. As shown, the upper housing base 90 can be secured to the upper housing intermediate member 92 via resilient clips 98. Standoffs or bosses 100 formed integrally with the intermediate member 92 space the intermediate member 92 from the PCB 94.

The lower housing member 14 includes a recess 102 which cooperatively receives a lower portion 80a of the base 80. The lower portion 80a defines a semi-spherical recess 80b (FIG. 4) in which a ball portion 104 of ball member 106 is removably received when the upper housing member 12 is in its rest or non-actuating position of FIG. 1. The upper housing member 12 includes the ball member 106 operatively connected thereto for sliding movement therewith. More particularly, a cube-shaped main body 108 of the ball member 106 is cooperatively received through an aperture 110 defined through lower housing base 90. A head portion 112 of the ball member 106, which is greater in size than the aperture 110, is cooperatively received within a recess 114 defined by walls 116 extending upwardly from the base 90. The upper housing intermediate member 92 includes downwardly depending walls 118 which wrap around or enclose the walls 116 when the upper housing base 90 is snapped together to the upper housing intermediate member 92. As shown, the resilient clips 98 can be formed by distal ends of the walls 118 and a shoulder portion defined in clip recesses 120 adjacent the walls 116. The upper housing intermediate member 92 can also sandwich a spring 122 between the head portion 112 of the ball member 106 and a central wall portion 92a of the intermediate member 92. The spring 122 urges the ball portion 104 of the ball member 106 in the shaped recess 80b of the lower housing base 80 for reasons that will be described in more detail below.

The micro-switches 36,38,40,42 are disposed on an underside of the PCB 94. These micro-switches 36,38,40,42 are selectively actuated by raised ramp portions 130 of the lower housing cover 84. More particularly, the lower housing cover 84 includes a raised ramp portion 130 corresponding to each of the micro-switches 36-42. In the illustrated embodiment, the micro-switches 36,38,40,42 have pivotally disposed actuator arms 36a,38a,40a,42a on the underside of the PCB 94 and hang in a non-actuated position. Engagement and movement by the corresponding raised ramp structure 130 pivots the pivotally disposed actuator arms 36a,38a,40a,42a

corresponding to micro-switches 36,38,40,42 to actuate the same. Other electrical components of the key fob 10 can also be disposed on the PCB board 94, such as the controller 32, the transmitter 28, the battery 34, and/or the antenna 44.

5 The lower housing intermediate member 82 defines a pair of tracks, including a first track defined on an upper side of the intermediate member 82 and a second track defined on an underside of the intermediate member 82. More particularly, the first track defined in the upper side of the intermediate member 82 is formed by grooves 132 that extend in a direction parallel to the first axis 16. The second track defined in the lower side of the intermediate member 82 is formed by underside grooves 134 that extend in a direction parallel to the second axis 18.

15 Riding in the first track grooves 132 is a first sliding mechanism 136. The first sliding mechanism includes ribs 138 that are received within the grooves 132 for guided movement therewith. A first biasing mechanism, such as the illustrated leaf springs 140, are secured within slots 142 defined on the 20 upper side of the intermediate member 82 for urging the first sliding mechanism 136 (and the upper housing member 12) to the rest, non-actuating position. A second sliding mechanism 144 has ribs 146 received in the underside grooves 134 for guided sliding movement therewith. A biasing mechanism, 25 such as illustrated leaf springs 148, urges the second sliding mechanism 144 (and the upper housing member 12) to the rest, non-actuating position. The springs 148 can be received within corresponding slots (not shown) defined in an underside of the intermediate member 82. The first track and its 30 grooves 132 and the second track and its grooves 134 both guide sliding movement of the first housing member 12 relative to the second housing member 14, as will be described in more detail below, and prevent relative rotation between the first housing member 12 and the second housing member 14.

35 The springs 140 (together comprising a biasing mechanism) urge the first sliding mechanism 136 to a central position along the track defined by the grooves 132. As shown, the first sliding mechanism 136 includes an aperture 154 through which the walls 116 and 118 of the upper housing base 90 and intermediate member 92 are received. Side walls 156,158 forming the aperture 154 abut corresponding side walls 118. As such, any movement of the sliding mechanism 136 along the track (defined by grooves 132) will cause the upper housing member 12, as well as the components 90,92,94 secured thereto, to move along the axis 16 guided by the track grooves 132. The springs 140 function to urge the upper housing 12 to its non-actuating, rest position along the axis 16 (i.e., the position between the first and third actuating positions).

40 In a similar fashion, the second sliding mechanism 144 has an aperture 160 defined therethrough. Side walls 162,164 of the aperture 160 abut the walls 118 such that movement of the second sliding mechanism 144 along the track grooves 134 will cause the upper housing member 12, and the components 90,92,94 secured thereto, to move along the axis 18 relative to 45 the lower housing member 14 (i.e., between the second and fourth actuating positions). Thus, the springs 148 function to urge the upper housing member 12 to its non-actuating, rest position between the second and fourth actuating positions.

46 The lower portion 80a of the base 80 defines a cross-shaped aperture 166 in which the ball member 106 is movable. More particularly, a first portion or arm 166a of the cross-shaped aperture 166 is defined in parallel with the first axis 16 and a second portion or arm 166b of the cross-shaped aperture 166 is defined in parallel with the second axis 18. When the first 50 housing member 12 is moved relative to the second housing member 14, the ball member 106 is moved by the walls 116 along with the upper housing member 12. As best seen in FIG. 55

4, movement of the ball member 106 along the cross portions 166a or 166b requires the head portion 112 of the ball member 106 to overcome the urging of the spring 122, which continuously urges the ball member 106, and particularly the ball portion 104, to a rest position wherein the ball portion 104 is received in the ball-shaped recess 80b. Once moved along one of the arms 166a or 166b, the ball member 106 is prevented from moving into the other of the arms 166a or 166b, which prevents simultaneous movement of the upper housing member 12 toward two actuating positions.

Through this arrangement, the ball member 106 is connected for movement with the first housing member 12 and the ball recess or detent 80b is defined as part of the lower housing member 14 (i.e., the recess 80b is particularly defined in the lower housing base 80, which is secured via screws 86 to the lower housing member 14). The ball member 106 is movable relative to the detent or recess 80b when the first housing member 12 is moved relative to the second housing member 14 to provide tactile feedback to the user. Accordingly, the ball portion 104 of the ball member 106 is received within the recess 80b when the upper housing 12 is in its non-actuating rest position; however, the ball portion 104 is moved out of the recess 80b when the upper housing 12 is moved into one of the actuating positions (e.g., the first, second, third or fourth actuating positions), but continuously urged back into the recess 80b by the spring 122. Alternatively, though not illustrated, the ball member 106 could be connected to the second housing member 14 and a detent or recess like recess 80b could be defined or connected to a component of the first housing member 12.

With reference now to FIG. 6, operation of the slide actuated key fob 10 will be described by way of example. More particular, FIG. 6 illustrates the upper housing member 12 being moved relative to the lower housing member 14 to the first actuating position along axis 16 and the direction of arrow 20. To effect this movement, a user would place his or her thumb or finger in the depression 24 to slide the upper housing member 12 relative to the lower housing member 14. In moving the upper housing member 12 relative to the lower housing member 14, the track grooves 132 would guide movement of the upper housing member 12 along the axis 16 and prevent relative rotation between the upper housing member 12 and the lower housing member 14.

With additional reference to FIG. 7, movement of the upper housing member 12 would require the first slide mechanism 136 to overcome the urging of the spring 140 disposed in the direction of the first actuating position (i.e., the spring 140 on the right side of FIG. 7). Likewise, such movement of the upper housing member 12 relative to the lower housing member 14 would require the user to overcome the urging of the spring 122 against the ball member 106. That is, the movement of the upper housing member 12 to the first actuating position would require the ball member 106 to move in the direction of arrow 170 (see FIG. 6) thereby compressing the spring and causing the ball portion 104 to move out of the detent or ball recess 80b. Such movement of the ball member 106 would provide tactile feedback to the user that the upper housing member 12 is no longer in its non-actuating, rest position. In addition, the cross-shaped aperture 166 would limit movement to the axis 16 once the ball member 106 begins movement in first arm portion 166a. As the upper housing member 12 moves toward the first actuating position, the raised ramp portion 130 associated with the first actuating position micro-switch 36 would cause the first micro-switch arm 36a to pivot (i.e., actuate the arm 36a). The controller 32 would then issue a first actuating signal, such as an unlock signal, through the transmitter 28 and antenna 44 to the

vehicle 30 so that the onboard controller 50 could take appropriate action (e.g., unlock the doors 52,54 via the mechanisms 56,58).

When the user would release the upper housing member 12 by removing his or her thumb or finger from the recess 24, the same spring 140 would urge the upper housing member 12 via the first sliding mechanism 136 back to the rest, non-actuating position. At the same time, the spring 122 would urge the ball member 106 back to its rest position wherein the ball portion 104 would again be received in the recess 80b. This again would provide tactile feedback to the user that the upper housing member 12 has returned to its rest position. Movement of the upper housing member 12 to the third actuating position would occur in the same way but would be against the other spring 140. In a similar manner, movement of the upper housing member 12 along the axis 18 to either of the second or fourth actuating positions would occur in the same way, except that the second sliding mechanism 144 would need to overcome the urging of the appropriate spring 148.

With reference now to FIG. 9, a sliding key fob 200 is illustrated according to an alternative embodiment. Except as indicated, the sliding key fob 200 is constructed like the key fob 10 and like reference numerals are used to refer to like components. More particularly, in FIG. 9, the key fob 200 includes a single slider 202. The slider 202 is disposed on rails 204,206 that could be parallel to a first axis, like axis 16. Instead of leaf springs, compression springs 208 flank the slider 202 on the rails 204,206 and urge the slider 202 to a rest position between first and third actuating positions. The rails 204,206 could have their distal ends secured into rail guide members 210,212. These rail guide members 210,212 can be disposed on rails 214,216 which could be parallel to a second axis, such as axis 18, for guiding sliding movement between second and fourth actuating positions. Compression springs 208 could be disposed on the rails 214,216 flanking either end of each of the rail guide members 210,212 for urging the rail guide members 210,212 and thus the slider 202 to the rest, non-actuating position between the second and fourth actuating positions. In most other respects, the slide actuated key fob 200 could operate like the key fob 10.

With reference to FIG. 10, another slide actuated key fob 300 is illustrated. Except as indicated, the sliding key fob 300 is constructed like the key fob 200 and like reference numerals are used to refer to like components. Instead of compression springs 208, the key fob 300 employs a single coil spring 302 for urging an upper housing member (not shown in FIG. 10) toward a non-actuating rest position relative to a lower housing member 14. In particular, one end 302a of the coil spring 302 (i.e., the more centrally positioned end) is fixedly secure to a central portion of the upper housing by anchor pin 304. Alternatively, the end 302a could be secured to one of the walls 118 or some other portion of the movable, upper housing member. The second or other end 302b of the coil spring is fixedly secured to the lower housing member 14 at a location radially spaced relative the location at which the end 302a connects to the upper housing member (at least when the upper housing member is in its non-actuating or rest position). Like the end 302a, the end 302b can be secured to the lower housing member 14 by an anchor pin, such as shown in FIG. 10, or through some other type of connection.

An outer coil portion 302c engages or abuts a wall or walls (e.g., walls 308 in FIG. 10) of the lower housing 14 defining a recess in which the spring 302 is received. This arrangement allows the upper housing to move relative to the lower housing 14 while being urged towards its rest position by the spring 302 and relative rotation between the upper and lower housing members is prevented. In most other respects, the

slide actuated key fob 300 operates and/or functions like the key fob 200. As a further alternative, though not illustrated, the coil spring 302 could be employed in the key fob 10 in place of the spring urged sliders or sliding mechanisms 142, 144.

With reference to FIG. 12, a slide actuated key fob 300 is shown for a vehicle according to still another alternate embodiment. The key fob 300 includes a housing 302 having a transmitter 304 (FIG. 13) disposed therein for transmitting actuation signals to an associated vehicle (e.g., vehicle 30). The key fob 300 can include a plurality of buttons disposed on the housing 302, including at least one slide actuated button (e.g. first slide actuated button 306 and second slide actuated button 308). As to be described in more detail below, the transmitter 304 disposed within the housing 302 sends an actuating signal corresponding to the slide actuated buttons 306, 308 when these buttons are each slideably moved in a first direction and subsequently depressed in a second direction.

More particularly, the transmitter 304 of the illustrated embodiment sends an actuation signal corresponding to one of the slide actuated buttons 306 or 308 only when that slide actuated button is first moved along a first axis on a face 310 of the housing 302 and then moved along a second axis into the housing 302. The other buttons 312, 314, and 316 disposed on the housing 302 in the illustrated embodiment can correspond to other remotely operated vehicle functions. For example, the button 312 can correspond to an unlock function, the button 314 can correspond to a lock function, and the button 316 can correspond to a panic function. These other buttons 312, 314, 316 can be conventional in that each is only required to be depressed into the housing 302 for actuation (i.e., no sliding movement is required to actuate these buttons).

While the illustrated embodiment includes two slide actuated buttons 306, 308 and three other buttons 312, 314, 316, it is to be appreciated that any number of slide actuated buttons can be provided and any number of other buttons (including no other buttons) can be provided. In addition, it is to be appreciated that other key fob configurations can be employed other than the illustrated housing 302.

With reference to FIG. 13, transmitter 304 disposed in the housing 302 transmits actuation signals to a vehicle, such as vehicle 30 of FIG. 11. The actuation signal transmitted can correspond to the button of the key fob 300 actuated (e.g., one of buttons 306-316). The key fob 300 can further include a controller 318 operatively connected to the transmitter 304 and powered by a battery 320. Micro-switches 322, 324, 326, 328, 330 can also be disposed within the key fob 300 for indicating when the buttons 306, 308, 312, 314, 316 are moved to their respective actuating positions. The controller 318, which is also operatively connected to the micro-switches 322, 324, 426, 328, directs the transmitter 304 to send respective actuating signals when the micro-switches 322-330 are actuated by the respective buttons. Accordingly, the transmitter 304 can send, via antenna 332, a particular actuating signal corresponding to whichever of the buttons 306-316 is actuated. Receipt of the actuation signals from the transmitter 304 car function as already described herein with respect to the vehicle 30 and its receiver 46, though other arrangement sand vehicles could also be used.

With additional reference to FIGS. 14A-14B, operation of the slide actuated button 306 is schematically illustrated in more detail. It is to be appreciated that the slide actuated button 308 can operate the same or similarly to button 306 and thus further detail concerning button 308 is not provided herein. For actuating the slide actuated button 306, the button

306, and particularly button actuator 348 of the slide actuated button 306, is sequentially slid along a first axis 340 in a first direction indicated or represented by arrow 342 and then depressed along a second axis 344 in a second direction as indicated or represented by arrow 346. The transmitter 304 disposed in housing 302 only sends an actuating signal corresponding to slide actuated button 306 when the button 306, and particularly the button actuator 348 thereof, is depressed sufficiently in the second direction indicated by arrow 346 (i.e., sufficient to actuate the micro-switch 322.) The button actuator 348 is prevented from being depressed in the second direction before being slidably moved along the first axis 340 and in the first direction 342 to an intermediate actuating position (i.e., the position shown in FIG. 14B).

As shown in the illustrated embodiment, the first and second axes 340 and 344, and likewise the first direction 342 and second direction 346, are oriented approximately normal relative to one another. Also in the illustrated embodiment, the first axis 340 and the first direction 342 are generally disposed along an outside contour of the housing 302 (i.e., along the face 310 of the housing 302) and the second axis 344 and the second direction 346 are oriented into the housing 302 and orthogonal relative to the face 310. In particular, the button actuator 348 is slideably movable in the first direction 342 along the axis 340 from a non-actuating rest position (FIG. 14A) to an intermediate non-actuating position (FIG. 14B) and then movable in the second direction 346 along the axis 344 from the intermediate non-actuating position to a depressed, actuating position (FIG. 14C).

The housing 302 and the arrangement of the button actuator 348 within the housing 302 prevents the button actuator 348 from moving in the second direction 346 toward the depressed, actuating position of FIG. 14C until first moved to the intermediate, non-actuating position of FIG. 14B. In particular, the micro-switch 322 is positioned so that the button actuator 348 actuates the micro-switch 322 when sufficiently depressed in the second direction 346. Since the controller 318 is operatively connected to the micro-switch 322 and the transmitter 304, the controller 318 directs the transmitter 304 to send the actuating signal corresponding to the button 306 when the micro-switch 322 is actuated by the button actuator 348. In contrast, the other buttons 312, 314, 316 are movable only in a single direction (i.e., into the housing 302) and the transmitter 304 sends corresponding actuation signals when these buttons are depressed in the single directions.

Sliding movement of the button actuator 348 along the first axis 340 from the first depressed position (FIG. 14A) to the second intermediate position (FIG. 14B) can be guided by at least one track, for example tracks 350, 352 shown in FIG. 15. To further facilitate the prevention of inadvertent operation of the button 306, the button actuator 348 can be urged toward its intermediate non-actuating position when moved therefrom in the second direction 346 and can be urged toward the non-actuating rest position when moved therefrom in the first direction 342. In one exemplary embodiment, a bias mechanism, such as schematically illustrated spring 354, can urge the button actuator 348 toward the non-actuating rest position of FIG. 14A when moved therefrom the first direction 342 and another bias mechanism, such as schematically illustrated spring 356, can urge the button actuator 348 toward the intermediate, non-actuating position of FIG. 14B when moved therefrom in the second direction 346.

In one exemplary embodiment, the button 306 can correspond to powered operation of a first vehicle closure on an associated vehicle (such as a powered-sliding door) and the button 308 can correspond to powered operation of a second vehicle closure on the associated vehicle (such as another

11

powered-sliding door). Of course, other functions can be associated with the buttons 306, 308. In another exemplary embodiment, the key fob 300 can include a slide actuated button that corresponds to a remote opening function of a powered vehicle closure, such as a tailgate or trunk.

The exemplary embodiment has been described with reference to the preferred embodiments. Obviously, modifications and alterations will occur to others upon reading and understanding the preceding detailed description. It is intended that the exemplary embodiment be construed as including all such modifications and alterations insofar as they come within the scope of the appended claims or the equivalents thereof.

The invention claimed is:

1. A slide actuated key fob, comprising:
a housing having a transmitter disposed therein, the housing including an upper surface having at least one elongated opening;
at least one slide actuated button moveably disposed in said at least one opening provided on said housing upper surface, said transmitter sending an actuating signal when said at least one slide actuated button is slidably moved in a first direction relative to said housing and subsequently depressed downwardly in a second direction toward said housing, wherein said at least one slide actuated button has an upper surface which is substantially coplanar with said housing upper surface as said at least one slide actuated button is slidably moved in said first direction.
2. The slide actuated key fob of claim 1 wherein said first and second direction are normal relative to one another.
3. The slide actuated key fob of claim 2 wherein said first direction is generally along an outside contour of said housing and said second direction is into said housing.
4. The slide actuated key fob of claim 1 wherein said at least one slide actuated button is slidably movable in said first direction from a nonactuating rest position to an intermediate nonactuating position and movable in said second direction from said intermediate nonactuating position to a downwardly depressed, actuating position, said at least one slide actuated button urged toward said intermediate nonactuating position when moved therefrom in said second direction and urged toward said nonactuating rest position when moved therefrom in said first direction.

5. The slide actuated key fob of claim 4 further including a bias mechanism that urges said at least one slide actuated button toward said nonactuating rest position when moved therefrom in said first direction.

6. The slide actuated key fob of claim 4 wherein said at least one slide actuated button is prevented from moving in said second direction toward said depressed, actuating position until first moved to said intermediate nonactuating position.

7. The slide actuated key fob of claim 1 wherein said housing has a micro-switch and a controller disposed therein, said micro-switch positioned so that said at least one button actuates said micro-switch when depressed in said second direction, said controller operatively connected to said micro-switch and said transmitter, and said controller directing said transmitter to send said actuating signal when said micro-switch is actuated by said at least one slide actuated button.

8. The slide actuated key fob of claim 1 wherein said at least one elongated opening is a first elongated opening and a second elongated opening spaced from said first opening, said at least one slide actuated button is a first button moveably disposed in said first opening that corresponds to powered operation of a first vehicle closure on an associated vehicle and a second button moveably disposed in said second open-

12

ing that corresponds to powered operation of a second vehicle closure on the associated vehicle.

9. The slide actuated key fob of claim 1 further including at least another opening on said upper surface of said housing and at least another actuated button disposed in said at least another opening that is movable in only a single direction, said transmitter sending another actuating signal when said at least another slide actuated button is depressed in said single direction.

10. The slide actuated key fob of claim 9 wherein said at least another opening is a first another opening and a second another opening spaced from said first another opening, said at least another actuated button is a first button moveably disposed in said first another opening that corresponds to locking of passenger doors on an associated vehicle and a second button moveably disposed in said second another opening that corresponds to unlocking of said passenger doors on the associated vehicle.

11. A key fob for a vehicle, comprising:
a housing having a slide actuated button disposed thereon;

and
a transmitter disposed in said housing for transmitting actuating signals to an associated vehicle, said transmitter sending an actuation signal only when said slide actuated button is first moved along a first axis on a face of said housing and then moved along a second axis into said housing,
wherein sliding movement along said first axis from a first rest position to a second intermediate position is guided by at least one track, a biasing mechanism urges said slide actuated button toward said first rest position, wherein said slide actuated button is only movable along said second axis into said housing after said slide actuated button is moved along said first axis from said first rest position to said second intermediate position.

12. The key fob of claim 11 wherein movement along said second axis into said housing actuates a micro-switch disposed on said housing.

13. The key fob of claim 11 wherein said slide actuated button corresponds to a remote opening function of a powered vehicle closure.

14. A key fob, comprising:
a housing including an upper surface having at least one opening, said opening having a first portion having a first depth and a second portion having a second depth greater than said first depth;
at least one slide actuated button moveably disposed in said at least one opening provided on said housing upper surface, said at least one slide actuated button sequentially slid in said at least one opening from said first portion toward said second portion in a first direction relative to said housing and then depressed downwardly in said second portion of said at least one opening in a second direction toward said housing; and
a transmitter disposed in said housing for sending an actuating signal when said at least one slide actuated button is depressed in said second direction after having been slid in the first direction.

15. The key fob of claim 14 wherein said at least one slide actuated button is prevented from being depressed in said second direction before being slidably moved in said first direction to an intermediate actuating position.

16. The key fob of claim 15 further including a biasing mechanism urging said at least one slide actuated button away from said intermediate actuating position back toward an initial rest position along said first direction.

13

17. The key fob of claim 14 wherein said first direction is disposed along a face of said housing and said second direction is normal relative to said first direction.

18. The key fob of claim 14 wherein a micro-switch is disposed on said housing and is located in said second portion

14

of said at least one opening, said micro-switch being actuated when said at least one slide actuated button is depressed in said second direction.
